(57) **CLAIM**

The ornamental design for a utensil, as shown and described.

DESCRIPTION

FIG. 1 is a top perspective view of a utensil showing our design;

FIG. 2 is a bottom perspective view thereof;

FIG. 3 is a top plan view thereof; and,

FIG. 4 is a side view thereof, the opposite side being a mirror image.

The broken line representations in the Figures are for the purpose of illustration only and form no part of the claimed design.
